MALCOLM K. PARKHURST, OF NEW YORK, N. Y., ASSIGNOR OF ONE-HALF TO LYNDON W. BURCH, OF YONKERS, NEW YORK

SELF-PROPELLED TOY

Application filed January 27, 1927. Serial No. 163,858.

This invention relates to toys of the self-propelled type in which a member is manually tensed in such a way as to react upon a driving member when the tension is being relieved.

The object of this invention is to simplify construction, add to efficiency in operation and render present known means more adaptable for cooperating with each other than heretofore. More particularly it relates to self-propelled toy water or land craft, the propulsion being applied to a rotary paddle or propeller at the rear of the toy and the paddle or propeller having roller elements whereby it may be used on smooth surfaces.

Other objects of this invention are to utilize resilient bands of rubber elastic or other equivalent material for mounting the paddle members in such a way that less friction will occur than would in case of the ordinary type of bearing connections. These resilient members may be readily renewed and fastened to the paddle or propeller member in case of breakage or weakening.

A further object is to provide means for tensing these resilient members by means of a ligature snubbed around the propeller member in such a way that pulling upon one end will rotate the propeller member in a reverse direction from which it turns in propelling the toy and as soon as the pull is released from the ligature member it may be retracted back into the toy without rotating the propeller.

A further object is to provide a float operated latching arrangement so arranged that as soon as the toy is placed in the water the propeller member will be released and the toy will be operated.

A still further object is to provide a bearing for the propeller member to relieve radial strain upon the resilient members while these members are being tensed. Owing to the fact that this bearing might be a latent cause of friction it is so designed as to be operative as a support for the propeller only during the tensing operation and not during the propelling operation.

Further and more definite objects and advantages will be described in connection with

the following specification, claims and drawings in which

Figure 1 represents a side view of the toy;

Figure 2 shows a top view with a part broken away to show the interior arrangement;

Figure 3 shows a sectional view of the rear of the device in which the ligature or cord member has been retracted for the tensing operation;

Figure 4 shows the arrangement of parts when a float operated catch is utilized to prevent the propeller from operating while the device is out of water;

Figure 5 shows a detail of the cord or ligature member as it is snubbed around the propeller member; and

Figure 6 shows a detail of the catch member.

1, in Figure 1, is the main body or frame member of the toy and 2 is the keel attached at the bottom for keeping the toy on a definite course when used in the water. The main housing 3 together with the pilot house 4 and the stack 5 enclose one end of the tensing cord or ligature 6 with its retracting element 7 attached to a fastening device 8 which is fastened into the frame member 1.

The paddle or propeller device 9 is mounted at the rear of the toy and is so arranged as to propel the toy forward after being wound up and released. It has also a rim 10 so that when placed on a flat surface it will roll freely, the front end being supported by the roller 11 also mounted in the frame member 1. The tensioning of the propeller is accomplished by pulling the knob member 26 fastened at one end of the cord member 6. The roller member 11 is mounted on an axle 12 so that it is free to rotate as shown in Figure 2 without friction against the sides of the frame member 1. This roller is made in a flat form so that it will cooperate with the keel to keep the toy on a more definite course when used in water.

As is more clearly shown in Figure 2 the paddle 9 is mounted in the opening 13 of the frame member 1. This opening is made large enough so that there is no possibility of the paddles rubbing on the frame. This

paddle is supported by means of elastic members 14 which are longitudinally tensed around a frame member and connected to the fastening means 15 in the paddling members. It is also desirable to insert these fastening members 15 in countersunk holes at the ends of the paddles so that a longer tensing member 14 may be used and greater resilience obtained.

Between the two paddle members is a partial supporting bearing 16, as more clearly shown in Figure 5, for preventing any undue strain on the resilient members 14 when the knob 26 is being withdrawn in the act of tensioning. As can be seen the cord 6 fastened to knob 26 is snubbed around the spool member 17 which is integrally connected to the paddle 9. When the knob 26 is withdrawn the spring action of member 7 is sufficient to prevent the cord 6 from sliding freely around the spool 17, which causes the spool and propeller to be rotated in a reverse direction from that taken by it while it is running freely. The tensioning member 7 and the resilient members 14 might as well be a metallic spring instead of the simple elastic members shown.

As is also shown more clearly in Figure 5 in addition to the friction between the spool 17 and the cord 6 produced by tension member 7, the friction between the supporting bearing 16 and the cord 6 caused by the rotating action produces a still further increase in friction between the cord 6 and spool 17. This friction also takes place during the tensing action but not during the propelling action. The reason for this is because as soon as the resilient members 14 begin their action a counteracting force is applied at the bottom of the propeller 9 to force it upwards and toward the front of the toy away from the bearing member 16. This in turn releases the cord member 6 from further friction with the spool 17 and allows the paddle to rotate freely.

Figure 3 shows the position of parts when the knob member 26 is retracted and the tensioning member 7 is extended. If the propeller 9 is not rotated sufficiently with one withdrawal of the knob 26 to tension the resilient members 14 sufficiently, the propeller may be held from rotation and the cord 6 allowed to be retracted so that another withdrawal of the cord 12 may be made until sufficient tensioning is applied to members 14.

When the propellers have been sufficiently tensioned a locking device such as is shown by 18 in Figure 4 may be used. This device with its catch 19 slips under the edge of one blade of the propeller 9 in such a way as to prevent its being rotated through the action of members 14 but not preventing it from being rewound by knob 26. This latch member is pivoted at 20 and has a stop pin 21 to prevent it from rotating too far towards the axis of the propeller in such a way that the

propeller might possibly throw it clear of the catching position. This might be possible if the latch were swung inwards so that the blade of the propeller would hit the nose 22 of the catch member 19 and knock it out of its 70 catching position.

The catch member is provided with an arm 23 to which is attached a flat slab of light material 24. As soon as the toy is placed in the water it is obvious that the float 24 will immediately attempt to rise as far as possible towards the surface of the water. This action will release the catch member and permit the propeller 9 to rotate freely through the action of resilient members 14. This catch arrangement may also be useful in tensioning members 14 by automatically preventing reverse motion as long as the toy is out of water.

Figure 6 more clearly shows the shape of the float member 24 together with the catch 18. The stop pin 21 is shown in such a position that it would abut the keel 2 of the toy but it is obvious that it may be placed in any position which would produce the same result desired, such as, in a position where it might contact with the main frame 1 of the toy. It is also provided with a pivot hole 25 to serve as a bearing on pivot 20 which is fastened to the keel 2.

In the operation of the device it is only necessary to tension the resilient members 14 by pulling knob 26. This tightens the cord 6 about the spool 17 against the retractile element 7 to such a degree that it rotates it in a clockwise direction as seen in Fig. 1. In addition to the friction of the cord on the spool due to the tension caused by element 7 there is also a tendency to push the spool 17 against the supporting bearing 16. This pressure also causes the cord 6 which is between the two to wrap itself still more tightly around the spool, adding to the friction already caused by the retractile element 7.

This rotation of the spool 17 winds the propellers to twist resilient elements 14. As soon as the knob 26 is fully withdrawn the paddles are manually or otherwise held, as by latch 18, and the knob is released. Owing to the pull of tension member 7 the spool 17 is drawn slightly away from its bearing 16 and since there is nothing to hold the end 26 of cord 6 it is immediately retracted by tension member 7 until it again touches or nearly touches the end of keel 2 through which core 6 slides without turning paddles 9 or releasing the members 14.

If the resilient elements are not now sufficiently wound this action can be repeated until enough energy is stored in them to propel the toy as far as desired.

Now when the toy is placed in the water and the paddle released by the rising of float 24 or otherwise it immediately begins to rotate in a counter clockwise direction. The thrust of the paddle in the water causing the 120

spool 17 to be slightly shifted away from bearing 16 thereby relieving it of any possible friction. The same is true when it is placed on a smooth surface. It is also raised somewhat by its buoyancy or the weight of the toy depending upon whether it is floating or rolling. In the rolling state the front end is supported by the wheel 11. The wheel being made flat also aids in keeping the toy on a constant course when floating.

In case of breakage or weakening of resilient members 14 they may be readily replaced by unhooking from fastening means 15 and a new member slipped in place. It is preferable to use two or more of such members, one or more on each end of the paddle, but one only may be used, in which case it would have to run through a hole in spool 17 and the full width of the boat.

It is not intended to be limited to the exact arrangements as shown but it is intended that any of a full range of equivalents may be substituted for any of the elements of the combination such as the use of a thrust propeller rather than the paddle arrangement disclosed, etc. In such a case the propeller would be arranged at right angles to the position shown and the resilient members 14 would be located towards the front and at the rear of the toy with the rewinding knob 26 arranged at the side. In such a case the bearing 16, would have to be arranged on some other member than the keel.

Having described my invention I wish to be limited only by the extent indicated and the combinations expressed in the following claims:

1. In a self propelling vehicle, resilient elements, a rotatable member supported by the resilient elements, means for tensing said elements consisting of a cord snubbed around the rotatable member, an elastic means, one end of the cord being attached to said elastic means for retracting it when the other end is released.

2. In a self propelling vehicle, resilient elements, a rotatable member supported by the resilient elements, means for tensing said elements consisting of a cord snubbed around the rotatable member, one end of the cord being attached to an elastic device for retracting it when the other end is released, said rotatable member having both rolling and liquid propulsion parts and a bearing for supporting the rotatable member when being acted upon by the cord to tense the resilient members.

3. In a self propelling vehicle, resilient elements, a rotatable member supported by the resilient elements, means for tensing said elements consisting of a cord snubbed around the rotatable member, an elastic means, one end of the cord being attached to said elastic means for retracting it when the other end

is released, and rotatable means mounted on the front portion of the vehicle.

4. In a toy boat, a rotatably mounted propeller, means for rotating the propeller comprising an elastic member capable of being rotatably tensed, said member also serving to keep one end of the propeller shaft in proper radial alignment, a catch device for holding the propeller stationary and a buoyant means operatively related to said catch device.

5. In a self propelling vehicle, resilient elements, a rotatable member supported by the resilient elements, means for tensing said elements consisting of a cord snubbed around the rotatable member, one end of the cord being attached to an elastic device for retracting it when the other end is released, a keel on the vehicle having a slot in its tail portion, the cord being placed in the slot and a knob at the end of the cord to prevent it from passing through the slot.

6. In a self propelling vehicle, resilient elements, a rotatable member supported by said resilient elements, means for tensing said elements consisting of a cord snubbed around the rotatable member, an elastic means, one end of the cord being attached to said elastic means for retracting it when the other end is released, the rotatable member having countersunk openings at its ends, connection means in said openings for connecting the resilient elements.

In testimony whereof I have signed this specification this 25th day of January, 1927.
